UNITED STATES PATENT OFFICE.

JOHN DYSON, OF DRACUT, MASSACHUSETTS, ASSIGNOR TO GEORGE M. ARRAGG, OF LAWRENCE, MASSACHUSETTS.

ATTACHMENT FOR SPINNING AND TWISTING FRAMES.

Application filed November 7, 1919. Serial No. 336,272.

To all whom it may concern:

Be it known that I, JOHN DYSON, a citizen of Great Britain, residing at Dracut, in the county of Middlesex and State of 5 Massachusetts, have invented certain new and useful Improvements in Attachments for Spinning and Twisting Frames, of which the following is a specification.

This invention relates to lifter motions 10 for spinning frames, especially cap spinning frames.

In such frames, as now made, part of the lifter mechanism comprises a revoluble shaft which terminates in a screw which revolves with a sleeve slidable on the shaft carried in bearings in the frame. When the bobbins are filled, the lifter mechanism should be in position so that the bobbin rail is down while doffing goes on, after which 20 the sleeve which carries a hand wheel is pulled out to disengage it from the driving gear, and the lifter and rail are forced up by hand.

After this is done, the parts are reset and 25 should be locked in position by means of suitable locks. Frequently, however, the operator forgets to lock the parts, and when the machine starts, the sleeve, with its gear, disengages from the driving gear, with the 30 result that the bobbin rail drops, breaking all the ends and causing other damage.

This invention consists of a spring so placed that the gears will automatically engage, thereby dispensing with the locking 35 mechanism.

In the drawings, Fig. 1 is an elevation from the front of a cap spinning frame showing the mechanism at one end, to which my invention is applicable.

40 Fig. 2 is a section on line 2—2 of Fig. 1 showing some of the parts.

Fig. 3 is an elevation of my spring removed from the machine, and Fig. 4 is an end view of Fig. 3.

45 Fig. 5 is an elevation, partly in section, showing another form of spring, and Fig. 6 is a section from the right on the line 6—6 of Fig. 5.

Fig. 7 is an elevation of another modified 50 form of spring. Figs. 8 and 9 show other forms of springs.

In the drawings, A represents the frame of a cap spinning machine having a stationary spindle rail B which supports spin- 55 dles 10 carrying caps 9, and C is a bobbin

rail carrying bobbins 11, which is raised and lowered by lifter mechanism of a well known type.

This lifter mechanism includes vertical rods 12 which carry rail C, and are moved 60 up and down by means of chains, such as 13, which run over pulleys 14 and 15 and are attached to a chain bar, such as 16, which has a vertical end at 17 against which bears the end of a screw 20.

The lifter shaft F terminates in screw 20 which passes through a relatively stationary bearing 22 and extends out through a sleeve 30 carried in bearings 23 fixed to the frame A of the machine.

70 This sleeve 30 is shown as carrying a collar 31 at the inner end and another collar 32 just outside the bearing 33, as well as collar gear K and hand wheel P. A suitable spline 8 fixed inside sleeve 30 rests in a 75 groove 8 in shaft F, whereby sleeve 30, with collars 31 and 32, gear K and hand wheel P, all of which are fastened together, are slidable on shaft F and revoluble therewith.

80 The driving gear H normally engages sleeve gear K, as shown in Figs. 1 and 2. When it is desired to raise rail C by hand, wheel P and the other parts carried by sleeve 30 are pulled out by hand to the 85 position shown in the dotted lines in Fig. 1, whereby gear K is freed from gear H and and the shaft F can be revolved to reset the parts.

85 Ordinarily a lock, such as shown at R 90 in Fig. 2, which is practically a gravity latch pivoted at 40 adapted to be dropped down outside of collar 32 or to be thrown back against a stop pin 41, is used for locking the parts in position. This is to prevent gears H and K from jarring apart, for if they do separate, the bobbin rail C drops and the ends break.

95 This invention consists of a spring, such as L, preferably of the helical compression 100 type, coiled around the sleeve 30 between collar 31 and that part of frame A which is represented by the bearing 23. This spring L so engages the collar and frame as to keep the sleeve gear and driving gear 105 normally in engagement and to engage them if the operator forgets to set the lock R.

I prefer to use a spring, such as shown in Figs. 3 and 4, wherein the ends 60 are turned back upon themselves at right angles 110

to the axis of the spring, thereby giving a steady bearing at both ends and avoiding the wearing of all raw ends against the collar 31.

5 As shown in Figs. 5 and 6, I may dispense with the lock entirely, and instead of having a spring which bears against the collar 31, I may use a bowed spring, such as M, having ears 50 at one end attached by 10 screws 51 to the frame, and extending thence downward at 53, terminating in a fork 54 which embraces sleeve 30 just outside of collar 32. It is manifest that when the parts are moved out, disengaging gears 15 K and H, spring M will be pulled out to the dotted line position, but will resume its normal position as soon as the parts are released. In Fig. 5, K and 32 are integral and, together with hand wheel P, are sweat- 20 ed, brazed, or otherwise fixed to sleeve 30.

Fig. 7 shows a spring S which is not bent around at the ends, but which may be made large enough so that it can be wound in on sleeve 30 or unwound therefrom by 25 working in one end and screwing it on.

As shown in Fig. 8 at D, I may use a flat wire coiled spring in place of L or S, or I may use a round wire spring G shown in perspective in Fig. 9 having a loop 70 30 for attaching it to frame A, a bow 71 and a loop 72 to extend around sleeve 30 and rest behind collar 32.

Springs such as L, S or D may be used with a lock such as R or springs such as M 35 or G in place thereof, and they may bear against any suitable collar such as 31 or 32 fixed to sleeve 30.

It is manifest that my invention may also be used on a twisting frame or other ma- 40 chine having a revolute and slidable gear such as K.

I claim:

1. The combination with a spinning ma- 45 chine having a frame, a movable bobbin rail and mechanism for raising and lowering such rail including a revolute shaft which terminates in a screw, a sleeve revolute with and slidable on said shaft, a driving gear, a sleeve gear revolute with the sleeve in po-

sition to engage and disengage said driving gear as the sleeve is slid along said shaft, and a collar carried by said sleeve, of a spring coiled around such sleeve which so engages the collar and frame of the machine as to keep the sleeve gear and driving gear normally in engagement. 55

2. The combination with a spinning ma- 60 chine having a frame, a movable bobbin rail and mechanism for raising and lowering such rail including a revolute shaft which terminates in a screw, a sleeve revolute with and slidable on said shaft, a driving gear, a sleeve gear revolute with the sleeve in po- 65 sition to engage and disengage said driving gear as the sleeve is slid along said shaft, and a collar carried by said sleeve, of a spring which so engages the collar and frame of the machine as to keep the sleeve gear and driving gear normally in engagement. 70

3. The combination with a machine hav- 75 ing a frame, a movable bobbin rail and mechanism for raising and lowering such rail including a revolute shaft which terminates in a screw, a driving gear, and a gear revolute with and slidable on said 80 shaft in position to engage and disengage said driving gear as it is slid along said shaft, of a spring which so engages the gear and frame of the machine as to keep the gear and driving gear normally in engage- 85 ment. 90

4. The combination with a cap spinning frame having a movable bobbin rail and mechanism for raising and lowering such rail including a revolute main shaft which terminates in a screw, of a sleeve revolute with and slidable on said main shaft, a driv- 95 ing gear, a sleeve gear revolute with the sleeve in position to engage and disengage said driving gear as the sleeve is slid along said shaft, a collar carried by said sleeve, and a spring coiled around such sleeve which so engages the collar and frame of the machine as to keep the sleeve gear and driv- 90 ing gear normally in engagement. 95

In testimony whereof I have affixed my signature.

JOHN DYSON.
